UNITED STATES PATENT OFFICE.

THOMAS A. MARSH, OF CHICAGO, ILLINOIS, ASSIGNOR TO GREEN ENGINEERING COMPANY, OF EAST CHICAGO, INDIANA, A CORPORATION OF ILLINOIS.

FURNACE.

1,326,361.

Specification of Letters Patent. Patented Dec. 30, 1919.

Application filed January 29, 1917. Serial No. 145,204.

To all whom it may concern:

Be it known that I, THOMAS A. MARSH, a citizen of the United States, residing at Chicago, in the county of Cook and State 5 of Illinois, have invented new and useful Improvements in Furnaces, of which the following is a specification.

This invention relates to improved features of construction for furnaces, and more 10 in particular of furnaces of the mechanical stoker type, whereby access may be more readily had to the grate, for the purpose of inspection or cleaning or for the making of adjustments of certain regulating devices 15 located within the combustion chamber.

Furnaces of the mechanical stoker type are ordinarily constructed in such a manner that the combustion chamber is not capable of access from the front of the furnace, because 20 of the presence of the fuel feeding and grate actuating devices, hence the control of the conditions within the furnace is largely dependent upon the regulation of said devices. In practice, however, proper conditions of 25 combustion cannot be always secured, and it is frequently necessary to correct faulty conditions by the manual application of tools, as, for instance for breaking up or removal of clinker formations, or otherwise 30 treating portions of the fuel bed. Inasmuch as the combustion chamber cannot be reached from the front of the furnace, it is proposed to provide a construction such that the grate may be reached, by the provision 35 of a compartment directly behind the combustion chamber, capable of entrance by a person and having a movable partition or door, which may be opened when it is desired to inspect or attend to the fire while 40 the furnace is in operation.

A further feature of the invention is the provision of an adjustable device operable from the rear of the combustion chamber and serving as a gate or retarding member 45 to control the discharge of the ash from the grate, and further to normally seal the space at the rear of the grate, but capable of being opened to permit access to the fuel bed for the purpose of inspection, the insertion 50 of tools, or removal of clinker formations.

A desirable construction for a furnace embracing the features of the invention is hereinafter more fully described in connec-

tion with the accompanying drawings, wherein—

Figure 1 is a view in vertical section of the rear portion of the combustion chamber of a furnace, and showing the features embodying the invention;

Fig. 2 is a view in horizontal section taken on line 2—2 of Fig. 1; and

Fig. 3 is a detail view in vertical section taken on line 3 of Fig. 1, showing the water-back and gate member in elevation.

Referring to the drawings, therein are 65 illustrated only such parts of the furnace as pertain to the invention, it being understood that a furnace to which the improved device is applicable is of the standard construction, embracing side walls 9 and front 70 and rear walls. At the forward end of the furnace is the combustion chamber or fire box of the furnace. A horizontal grate 10, preferably of the endless chain type, is mounted within the combustion chamber 75 and upon a supporting structure 11, embracing sprocket wheels 12 at the front and rear ends thereof, there being provided suitable actuating mechanism for moving the grate. As illustrated in the drawings, the 80 rear portion of the grate 10 is shown, the same being mounted on the rear sprocket wheels 12, carried upon a transverse shaft 13 journaled in the supporting structure. Immediately above the rear end of the grate 85 and spaced a considerable distance therefrom, is a cross-wall 14, extending transversely of the combustion chamber and forming the rear wall thereof. The cross-wall is constructed of brick and preferably 90 supported upon a series of longitudinal and parallel beams 15, of I-beam section, which in turn rest or are supported upon another series of cross-beams 16, of I-beam section, extending transversely below the cross-wall 95 14 and beams 15 and mounted at their ends in the side walls of the furnace. The lower cross-beams 16 are preferably arranged by locating one I-beam at the rear ends of the upper longitudinal beams 15 and a pair of 100 such beams 16 located in closely spaced relation intermediate the ends of said upper beams 15. Immediately to the rear of the cross-wall 14 is a portion of the water tube boiler of the furnace, namely, the lower 105 drum 17, the remaining part of the boiler

occupying the space above the combustion chamber and throughout the length of the furnace. Immediately below the drum 17 and extending rearwardly from the rear-
5 most cross-beam 16, is a horizontal parti-
tion wall 18, serving to separate the space
therebelow from the space above, wherein
is located the boiler. This horizontal wall
extends rearwardly to a vertical wall 19 of
10 brick, which may be the rear wall of the
furnace or a separate wall spaced inwardly
therefrom and resting upon the foundation
of the furnace. Immediately below the
rearmost cross-beams 16 and adjacent the
15 forward end of the horizontal wall 18, is
a vertical partition wall 20 provided with
doors, as will hereinafter be pointed out,
said partition wall extending from the un-
der surface of the forward end of the hori-
20 zontal partition wall downwardly below
the grate and terminating just above the
floor 21 of the furnace and supported upon
a short vertical wall 22 projecting upwardly
from the foundation. As a preferable con-
25 struction, the vertical partition wall 20 con-
sists of a rectangular frame 23, made up
of angle-members supported in the sur-
rounding walls and a central vertical wall
section 24 dividing the frame 23 into two
30 openings at either side thereof. Hinged to
outer vertical frame members are two metal
doors 25, 25, adapted to close the openings
in the partition wall and arranged to swing
rearwardly on suitable vertically arranged
35 hinges 26, there being provided suitable
latches or catches 27 on the adacent edges
of the doors and the central section 24 for
locking the doors in closed position.

It is manifest that the horizontal wall 18,
40 the rear wall 19, and the partition wall 20,
inclose a space which forms a chamber or
compartment located in close proximity to
the rear of the combustion chamber, and of
sufficient size to permit a person to stand
45 erect therein and to work with freedom. An
entrance or door 28 is provided in the side
wall 9, permitting access to the chamber
from the exterior of the furnace. By means
of this chamber a man may enter the in-
50 terior of the furnace immediately behind
the combustion chamber, and, by opening
one or both of the doors 25, 25, is enabled
to inspect the grate, to attend the fuel bed,
or make adjustments of the devices herein-
55 after described.

Referring now to the adjustable gate
member and associated parts, there is pro-
vided immediately below the front margin
of the cross-wall 14 a water-back, compris-
60 ing two water-circulating tubes 29 and 30,
extending transversely of the combustion
chamber above the grate and arranged verti-
cally one above the other, the upper tube
29 being located adjacent to the under sur-
65 face of the cross-wall and preferably in con-

tact with the longitudinal supporting beams
15, and the lower tube 30 located vertically
below the upper tube and spaced a short
distance therefrom and substantially mid-
way between the surface of the grate and 70
the under surface of the cross-wall. The
water-back of tubular formation primarily
serves as a retarding member, extending
above the grate and defining the opening for
the discharge of ashes from the grate, the 75
same being preferably water cooled to pre-
vent the adhesion of clinkers thereto, thus
keeping the discharge opening free from
accumulation of clinkers. Immediately be-
hind the upper tube 29 is mounted a trans- 80
verse baffle plate 31, secured to the beams
15 and comprising a substantially T-shaped
member, depending from the under surface
of the beams 15, below the upper tube, and
inclined forwardly toward the lower tube, 85
the lower margin of the baffle plate 31 hav-
ing contact along the upper surface of said
lower tube, thereby closing or sealing the
space between the tubes.

Pivotedly mounted within the space to the 90
rear and above the grate, are the adjustable
gates or retarding members 32, 32, compris-
ing vertically arranged plates extending
transversely of the grate between the side
walls of the furnace and located immedi- 95
ately behind the tubes 29 and 30 and below
the fixed plate 31. As a preferable construc-
tion, the gate members consist of two sec-
tions, each extending throughout one-half
of the width of the grate and each supported 100
and operating independently of the other.
The plates 32, 32 are movably mounted, as
will hereinafter be described, to swing ver-
tically in the space immediately behind the
tubes 29 and 30, and in operative position 105
extend from the lower tube downwardly in
close proximity to the grate surface, the
space below the gate members being the
discharge opening for the ashes. The plates
32, 32 are supported or secured to the ends 110
of horizontal arms 33, 33 attached to the
rear surfaces of the plates, each plate being
provided with two arms at the ends thereof.
The arms extend rearwardly and are rigidly
mounted upon, or keyed to, rotatable shafts 115
34, 34, each shaft extending throughout the
length of its associated plate and in axial
alinement with each other. The shafts 34,
34 are journaled in bearings 35 secured be-
tween the lower flanges of the forward pair 120
of cross-beams 16, 16 and midway between
the ends of the beams 15. The bearings 35
are preferably three in number, one at the
outer ends of each shaft and a central bearing
supporting the adjacent ends of each 125
shaft. The arms 33 are preferably of V-
form, thereby providing the divergent arms
extending from the pivotal point and joined
to the plates adjacent to their upper and
lower margins, by means of bolts or con- 130

necting members 36. The plates 32 are, by this manner of mounting, free to be rotated about the axis of the shafts, the plates being preferably curved transversely and in the arc of a circle taken about the axis of rotation of the shafts 34, 34.

As a means for operating the gate members, the following construction is employed: One arm of each plate, preferably the arms adjacent the side walls of the furnace, is provided with a rearwardly extending boss 37, in which is rigidly secured an operating lever 38, terminating adjacent the rear doors 25, 25 of the partition wall 20. Mounted upon the side wall of the furnace and adjacent to each of the levers 38, 38, is provided a quadrant 39, arranged vertically and adjacent the plane of the movement of the levers. The quadrants 39, 39 are provided throughout their lengths with a series of apertures 40, located between the margins thereof and spaced suitable distances apart. The purpose of the quadrants is to provide means for holding the gate members in any desired position of adjustment, this being accomplished by the provision of a pin or stop member 41, adapted to be inserted in one of the apertures 40 and engaging the levers to prevent the upward swinging movement thereof.

When the furnace is in operation, the normal position of the gate member is below the lower tube 30, with its lower margin spaced a predetermined distance above the surface of the grate, thereby defining the size of the discharge opening for the ashes, as well as serving as a retarding member to retain the layer of fuel above the discharge opening within the combustion chamber until it has been fully consumed and reduced to ash. The space above the gate is closed by the tubes 29 and 30 and the fixed plate 31, said members serving also to retard the upper layer of fuel, and also acting, in conjunction with the gate members, to seal the space between the grate and the cross-wall and above the discharge opening.

To operate one or both of the gate members, a person enters the rear chamber and, opening the doors, can manipulate the operating levers and thus swing the gate members, either to vary the size of the discharge opening, or completely open the space, by rotating the same upwardly to their fullest extent. The gate members being removed from such space, free access may be had to the fuel bed at the rear of the grate, either for the purpose of inspection or for the introduction of tools for the purpose of cleaning.

The purpose of the compartment located at the rear of the combustion chamber is now evident, namely, that it permits a person to approach in close proximity to the grate while the furnace is in operation, and,

by opening the doors, to inspect the condition of the fuel bed and, if necessary, employ a hook, splice bar, or other suitable tool, either to loosen up portions of the fuel bed, or to remove large clinker formations, which otherwise could not pass through the discharge opening.

The constructing of the gate members in two or more sections, rather than a single section, is advantageous in that it permits one portion of the grate to be inspected and cleaned without disturbing the remaining portion of the grate, thereby avoiding the loss of unburned fuel that would be discharged from the portion not requiring attention.

In brief, the features embodied in the furnace herein described make it possible to give the fuel bed the required attention, in spite of the inaccessibility of the combustion chamber from the front of the furnace, as is the case in most furnaces of the mechanical stoker type, thereby greatly increasing the possibility of efficient and proper handling and operation of furnaces so equipped.

I claim as my invention:

1. In a furnace, the combination of a combustion chamber, a grate mounted in said combustion chamber, a compartment formed at the rear of the furnace and communicating with said combustion chamber, and a fuel-retarding member adjustably mounted above the rear end of the grate and operative from said compartment.

2. In a furnace, the combination of a combustion chamber, a grate mounted in said combustion chamber, a compartment at the rear of said combustion chamber, a vertical partition wall separating said combustion chamber and said compartment and provided with an opening therein, a closure for said opening, and a fuel-retarding member adjustably mounted above the rear end of the grate and capable of access from said compartment through the opening in said partition wall.

3. In a furnace, the combination of a combustion chamber, a grate therein, a fuel retarding plate adjustably mounted above the grate adjacent the rear end thereof, and comprising arms connected with said plate and having pivotal connection with fixed parts of the furnace structure at a point to effect the movement of said plate in a path at right-angles to the surface of said grate, and means for retaining said plate in any of its adjusted positions.

4. In a furnace, the combination of a combustion chamber, a grate therein, a fuel retarding member comprising a plate adjustably mounted above the grate adjacent the rear end thereof and adapted to move in a path at right-angles to the surface of said grate, arms extending rearward from said plate and having pivotal connection

with fixed parts of the furnace structure, and means for engaging said arms for holding said plate in any of its adjusted positions.

5. In a furnace, the combination of a combustion chamber, a grate mounted in said combustion chamber, a partition wall spaced rearwardly from said grate, a door in said partition wall, a cross-wall extending over the rear end of said grate, an adjustable fuel-retarding member pivotally mounted intermediate the grate and said partition wall and comprising a gate member vertically adjustable above the rear end of said grate, and operating means adjacent said vertical partition wall, the same being operable through the doorway in said partition wall.
6. In a furnace, the combination of a combustion chamber, a grate mounted in said combustion chamber, a compartment spaced rearwardly from said grate provided with a door communicating with the combustion chamber, a cross-wall extending over the rear end of said grate, a fixed fuel-retard-
- 10
- 15
- 20
- 25

ing member depending from said cross-wall, and a gate member adapted to open and close the space below said fixed fuel-retarding member and capable of adjustment through the doorway in said compartment. 30

7. In a furnace, the combination of a grate mounted in the combustion chamber of the furnace, a compartment at the rear of said combustion chamber adapted to be entered from the exterior of the furnace and embracing a wall separating the combustion chamber therefrom, a door in said wall, a fuel-retarding member pivotally mounted above the rear end of said grate, and an operating lever adjacent said door and operable therethrough from said compartment. 35

In testimony that I claim the foregoing as my invention, I affix my signature in the presence of two witnesses, this 13th day of January, A. D. 1917.

THOMAS A. MARSH.
